Fig. 3

Fig. 4

FIG. 1 is a perspective view of a grocery bag packer embodying my new design.

FIG. 2 is a side elevational view of the same.

FIG. 3 is a top plan view of the same.

FIG. 4 is a perspective view of a modified form of the grocery bag packer shown in FIG. 1.

The characteristic features of my design reside in the side mounted supporting portions, the broken line representation of a grocery bag in FIG. 2 being for purposes of illustration only.

What I claim is:

The ornamental design for a grocery bag packer, as shown and described.
